UNITED STATES PATENT OFFICE.

JOSEPH S. DUNCAN, OF CHICAGO, ILLINOIS, ASSIGNOR TO ADDRESSOGRAPH COMPANY,
OF CHICAGO, ILLINOIS, A CORPORATION OF ILLINOIS.

RIBBON-INKING MECHANISM FOR PRINTING-MACHINES.

1,031,541.

Specification of Letters Patent.

Patented July 2, 1912.

Application filed August 17, 1908. Serial No. 448,938.

To all whom it may concern:

Be it known that I, JOSEPH S. DUNCAN, a citizen of the United States, residing at Chicago, in the county of Cook and State of Illinois, have invented new and useful Improvements in Ribbon - Inking Mechanism for Printing-Machines, of which the following is a specification.

The object of this invention is to provide 10 a ribbon inking mechanism for printing machines and more particularly for addressing machines of the general type illustrated in my former Patents No. 764,660 dated July 12, 1904 and No. 803,677 dated Nov. 7, 1905. 15 In this class of addressing machines, the addresses are set up in type in suitable holders or produced on plates and fed one at a time from a magazine to printing position.

The invention has for its object to ink the 20 address form with an inking ribbon and to so arrange and feed the ribbon that it will ink the form evenly and wear uniformly.

A further object of the invention is to utilize the full width of the ribbon for inking purposes and to arrange and feed the ribbon so that a fresh part thereof will engage each form and without being fed the length of a form.

In the accompanying drawings which 30 illustrate the invention as it may be embodied in an addressing machine, Figure 1 is a plan view showing as much of the addressing machine as is necessary to understand the adaptation and operation of the 35 invention. Fig. 2 is a front elevation; partly in section, of the structure shown in Fig. 1. Figs. 3 and 4 are detail views showing the feed mechanism in different positions. Fig. 5 is an elevation at one side of the machine. 40 Fig. 6 is a perspective view of one end of the mechanism. Fig. 7 is a detail elevation view, partly in section, of the end of the mechanism illustrated in Fig. 6.

In the particular embodiment of the invention illustrated in the drawings, the printing plate 8 is arranged in a holder 9 and the latter is moved to printing position by a carrier consisting of the endless chains 10. These chains are guided in the frame 50 11 and move the printing devices one at a time from a magazine to printing position above the bed 12. Any suitable means may be provided for operating the chains such as the sprocket wheels 13. The sheet or en-

velop to be printed is placed upon a plate 55 14, which may be termed an envelop plate for convenience, which is pivotally mounted at 14' on the carrier frame, and this plate has an opening 15 through which the impression is made.

The ribbon 16 is carried by two spools 17, 18 which are mounted on shafts 17', 18' journaled in suitable bearings in the frames 17'' and 18'' supported on the main frame 19 on opposite sides of the carrier frame 11. 65 The shafts 17' and 18' are arranged in parallel relation with each other and in angular relation to the direction of movement of the printing devices to printing position, and the ribbon is thus arranged to pass 70 through printing position diagonally to the direction of movement of the printing devices to printing position. Thus the ribbon will extend across the printing device in a diagonal direction to the lines of type thereon 75 and as the ribbon is fed transversely to the direction of movement of the printing device to printing position the effect is to feed the ribbon sidewise as well as endwise with relation to the position usually occupied by the 80 lines of type in the printing device when in printing position. It is to be observed that the address forms usually comprise several 85 lines of type and if the ribbon were fed in the direction at right angles to the direction of movement of the printing device to printing position the result would be that the greater proportion of those parts of the ribbon which engage the type form of one 90 printing device would also engage the type form of successive printing devices unless the ribbon were fed at each operation a distance equal to the length of an address form, and in either event there would be the further result that the ribbon would only be 95 used in continuous paths corresponding to the lines of type. But by arranging the ribbon diagonally to the direction of movement of the printing device to printing position the feeding of the ribbon may be so timed and regulated that entirely fresh parts of the ribbon, or substantially so, are moved to inking position for each successive printing device and this feeding movement of the ribbon is comparatively slight and very 100 much less than the length of an address form. This arrangement and operation of the ribbon feeding mechanism also enables

the use of substantially the entire width of the ribbon so that after the ribbon has been fed from one end to the other its entire surface, or practically so, has been utilized for inking the forms.

The mechanism for feeding the ribbon comprises ratchet wheels 20, 21, mounted on the shafts 17', 18' and arranged to be engaged by pins 20', 21' on dogs 20'', 21'' which are pivotally mounted on studs 20''' 21''' carried by a feed bar 22. A lever 23 is pivotally mounted on the frame 17'' and it is provided with a cam surface 23' which is engaged by a roller 24 on an arm 24' on the 15 pedal lever 25 which operates the platen (not shown) of the machine. A spring 26 is attached at one end to the main frame 19 of the machine and at its other end to the cam lever 23 which is suitably engaged with 20 one end of the feed bar 22 (Fig. 1). The cam lever and the spring reciprocate the feed bar.

A shifting bar 27 is arranged alongside the feed bar 22 and is adapted to be moved 25 endwise. This shifting bar carries two releasing devices for operating the dogs 20'', 21'' and these devices comprise arms 28, 29 pivotally mounted at one end 28', 29' on the shifting bar and provided at their other 30 free ends with sockets 28'', 29''. The ribbon spools are made alike and a description of one will be sufficient. Each spool comprises a core 30 which is composed in part 35 of a wing 31 eccentrically and pivotally mounted in the ends 32 of the spool. The core is recessed at 30' to receive the wing 31 so that when the wing is closed against the core it will provide a smooth and even 40 surface on which the ribbon may be wound evenly. The end of the ribbon is fastened to the free end 31' of the wing in a suitable manner (Figs. 6, 7) and the arrangement is such that when the ribbon has been fed off of one spool the wing 31 will be swung out 45 from the core as shown in Fig. 7. A finger 33 is mounted beyond the spool on one pivot stud 33' of the wing 31 and it is arranged to engage a projection 34 on the adjacent release arm 28. This description of the spool 50 has been directed to the construction of spool 17 which is illustrated in Figs. 6 and 7 but it will be understood that the spool 18 is similarly provided with a wing to which the other end of the ribbon is attached and 55 a finger 35 is mounted on one pivot stud 35' of the wing of spool 18 to engage the projection 36 on release arm 29 (Fig. 1). The release lever 28 has a lug 37 and the release lever 29 has a lug 38, and these lugs are 60 arranged and adapted to support the dogs 20'' and 21'' out of operative relation to the ratchet wheels 20 and 21, as hereafter described.

When the ribbon is being fed from right 65 to left the dog 21'' will engage and operate

the ratchet wheel 21 and the dog 20'' will engage the lug 37 and be thereby prevented from engaging its ratchet wheel 20 (Fig. 3). When the ribbon is being fed from left to right the dog 20'' will operate its ratchet wheel 20 while the dog 21'' will be prevented from engaging its ratchet wheel 21 by the lug 38. The feeding movement is effected by the platen lever which operates the cam lever 23 and moves the feed bar endwise in one direction and by the spring 26 which moves the feed bar endwise in the other direction returning it to normal position, and it depends entirely upon the position of the shifting bar as to which of the dogs will operate. In Fig. 3 the dog 21'' will engage and operate the ratchet wheel 21 with each endwise movement of the feed bar to the left, and in Fig. 4 the dog 20'' will engage and operate the ratchet wheel 20 with each 70 endwise movement of the feed bar to the right. The endwise movement of the feed bar to the left is the result of the direct movement of the cam lever and the endwise movement of the feed bar to the right is produced by the spring 26. Assuming that the ribbon is traveling from right to left, and referring particularly to Figs. 6 and 7, when the pull on the ribbon raises the wing 31, as shown in Fig. 7, the finger 33 will engage 75 the projection 34 and swing the socketed end 28'' of the release arm upward in position to be engaged by the pivot stud 20''' of the dog 20'' on the next endwise movement of the feed bar. It will be observed that the stud 20''' projects through the dog 20'' so that it may enter the socket 28'' of the release arm 28 and when it is so engaged the spring 26 is strong enough to shift the bar 27 endwise and carry the lug 37 away from the dog 20'' and the lug 38 into position to engage the dog 21''. When the wing of the spool 18 is similarly raised the bar 27 will be shifted in the opposite direction to produce a reversal of movement of the ribbon. This reversal of movement of the ribbon is thus effected automatically whenever the ribbon is fed entirely off of one spool to operate its wing. 80

The shifting bar is locked in position 85 when moved in either direction by a roller 39 which is carried on an arm 40 pivoted at 40' on a bracket 41 secured to the frame 17''. A block 42 is mounted on the shifting bar 27 and is guided in a slot 41' in 90 the bracket 41. This block is provided with a shoulder 43 and a spring 44 is attached to the arm 40 and the bracket and normally holds the roller 39 seated against the block on one or the other side of the shoulder 43. 95 The spring 44 will yield sufficiently to permit the shoulder 43 to ride over the roller 39 when the bar 27 is shifted but in either 100 position of the bar the roller is engaged with the block against the shoulder in a 105 110 115 120 125 130

manner to prevent the bar from accidentally moving or creeping. A form 45 may be arranged in an opening 46 in the envelop plate 14 and supported in any suitable manner, as for example on the frame 18", to print a date or other matter alongside of the address.

While the invention is particularly adapted for addressing machines as herein shown 10 and described it is not limited to this adaptation and it may be used in connection with any other printing machine to which it can be applied. When the ribbon has been fed from one spool to the other it is automatically 15 reversed and the operation may be repeated as long as sufficient ink remains in the ribbon to ink the forms.

What I claim and desire to secure by Letters Patent is:

- 20 1. In a printing machine, the combination of a pair of spools, an inking ribbon arranged to wind and unwind on said spools, means for feeding the spools alternately for winding the ribbon from one to the other, 25 said feeding means comprising a pair of ratchet wheels mounted to turn with the spools, a reciprocatory feed bar, means for positively actuating said bar in one direction, yielding means for actuating said bar 30 in the other direction, a pair of dogs pivotally mounted on said feed bar to engage said ratchet wheels, and means comprising, a shifting bar and, dog-retaining devices for alternately moving said dogs relatively to 35 the feed bar into released position to reverse the ribbon winding operation.
2. In a printing machine, the combination of a pair of spools, an inking ribbon arranged to wind and unwind on said spools, 40 means for feeding the spools alternately to wind the ribbon from one to the other, said feeding means comprising a pair of ratchet wheels mounted to turn with the spools, a reciprocatory feed bar, a pair of dogs mounted on said feed bar in position to engage 45 said ratchet wheels, and means for reversing the ratchet feeding operation, comprising a shifting bar, devices on said bar for maintaining said dogs in inoperative position, arms pivoted on said shifting bar and 50 adapted to be operated from the feed bar, and means for positioning said arms to be
- actuated by the feed bar to operate the shifting bar.
3. In a printing machine, the combination 55 of a pair of spools, an inking ribbon arranged to alternately wind and unwind on said spools, means for feeding the spools to wind the ribbon from one to the other, said means comprising a pair of ratchet wheels 60 setired on the spools, a reciprocatory feed ba. and a pair of dogs on said feed bar to engage the ratchet wheels, and means for reversing the ratchet feeding operation, comprising a shifting bar, means carried by the 65 shifting bar to alternately raise the dogs out of operative position, a pair of arms pivoted on the shifting bar, and a movable part pivoted on each spool adapted to be actuated by the ribbon, to place said arms in position to be actuated from the feed bar, whereby to throw one dog out of engagement with the ratchet wheel and permit the other to engage with the ratchet wheel to wind the ribbon in an opposite direction. 70
4. In a printing machine, the combination 75 of a pair of spools, an inking ribbon arranged to wind and unwind on said spools and extending therebetween through printing position, means for feeding the spools alternately to wind the ribbon from one to the other, said means comprising a pair of ratchet wheels mounted to turn with the spools, a feed bar adapted to be reciprocated, 80 a pair of dogs on said feed bar to engage the 85 ratchet wheels, one of said dogs being in released position when the other is in operative position, a pair of studs on said feed bar, a shifting bar, arms on said shifting bar pivoted at one end thereto and provided with sockets at their free ends, a movable part on each spool to which the end of the ribbon is attached and which is actuated as the ribbon is exhausted from the spool in unwinding, and means operated by said 90 movable part and adapted to actuate said arm to cause the socketed end thereof to engage one of said studs, for the purpose described. 95
